HEAT EXCHANGER

Daniel Raymond McNeal, Abington, Pa., assignor
to Andale Company, Philadelphia, Pa., a corporation of Pennsylvania

Application May 15, 1942, Serial No. 443,088

2 Claims. (Cl. 257—222)

This invention relates to heat exchangers and particularly to that type which is known as a tube and shell exchanger wherein a bundle of tubes is enclosed within a surrounding shell, there being provided suitable passages and connections for circulating one of the fluids through the interior of the tubes and the other fluid around the exterior of the tubes.

The primary objects of the invention are to provide an exchanger of the tube and shell type in which the tube bundle can be inserted or removed without disturbing any of the piping connections for either of the fluids and in which all possibility of leakage of one fluid into the other fluid is prevented while, at the same time, providing a construction by means of which it is possible to utilize for each of the fluids whatever kind of metal or alloy is best suited for the particular installation in question. The following specific example will emphasize the importance and value of the improvements disclosed herein by means of which I have attained these primary objectives.

Exchangers of the tube and shell type are often used in connection with the cooling of oil, and in many installations of this kind the oil is frequently very hot and also under considerable pressure, so that the structure must be made of substantial strength. Furthermore, the units may be used in situations where any damage to the cooler may result in dangerous fires and possible death. This is particularly true in marine installations where the escape of highly heated oil would imperil the safety of the passengers and crew. This has been emphasized during the present war emergency, during which so many naval as well as merchant vessels are being involved in dangerous combat.

In marine installations the cooling medium is generally sea water which, of course, has a strongly corrosive action on steel. For this reason it has heretofore generally been customary to make the shell and its fluid connections of bronze or of some other corrosion resistant alloy instead of steel. Alloys of this kind, however, have a far less factor of strength and generally melt at a far lower temperature than does steel, so that in the event of damage to the boat such as would be caused, for example, by a torpedo, a shell made of such resistant alloy is far more liable to rupture or melt and permit the escape of the contained oil than is a steel shell. This naturally greatly increases the fire hazard and the possible danger to life.

With the foregoing specific situation in mind, the principal objects of my invention, as stated above, will be more fully appreciated. I wish it to be understood, however, that the usefulness of the invention is not in any way to be limited to the specific instance described but is equally applicable to any situation where it is advanta-

geous to make the flow path of either or both of the fluids involved of some specific metal or alloy so as to meet special conditions of service as, for example, in the chemical industry.

5 Additional objects of my invention are to provide a tube and shell heat exchanger in which it is possible to save a large percentage of any expensive special alloy which may be required for one of the fluids while at the same time retaining all of the strength and rigidity which may be necessary for the particular installations in question; the provision of a construction in which a special, separable and readily replaceable tube-circulation connection member is provided for completing the circulating path of one of the fluids involved, generally the cooling fluid which, in my improved device, passes through the interior of the tubes; the provision of a construction in which all joints are maintained in absolutely leak-proof condition by clamping my improved connection member between the customary, movable main head of the exchanger and a suitable supporting flange on the exterior of the shell; and in general to overcome certain difficulties incident to previous constructions while at the same time in no way interfering with other necessary and important features.

How the foregoing objects, together with any other objects which may appear hereinafter or are incident to my invention, are attained, is illustrated in preferred form in the accompanying drawings, wherein—

Figure 1 is a vertical longitudinal section through a heat exchanger embodying my improvements;

Figure 2 is a plan view of my improved connecting member for the fluid which is passed through the tubes, and

Figure 3 is a side elevation of the upper portion of my improved device with the shell, the connecting member, and the main head separated slightly in order to more fully illustrate the manner in which they are assembled.

The drawings illustrate a specific embodiment 45 of the invention which is intended for the cooling of oil so that the following description will be directed thereto although, as stated above, it is not intended to limit the invention to this field of service.

50 The shell 4 of my improved heat exchanger encloses a tube-bundle 5. The upper ends of the tubes are mounted in the fixed or stationary tube sheet 6 while the lower ends are secured in the floating tube sheet 7 against which is mounted the lower or floating head 8. The oil to be cooled passes around the exterior of the tubes and is conducted to and from the shell through the passages 9, 10, 11 and 12, the oil in its passage through the shell being circulated back and forth 55 across the tubes by means of the customary baffle plates 13 in a manner well understood in

this art. The passages 9 to 12 are under the control of a valve 14 which can be turned either to the position indicated in the drawings where all of the oil is sent through the cooler or to any intermediate position where the oil can be divided so as to deliver any desired proportion of it to the cooler and by-passing the remainder, depending upon the temperature of the oil.

The tube sheet 6 fits against a seat 15 around the open upper end of the shell, and between the tube sheet and this seat is located a suitable gasket 16. Over the upper face of the tube sheet 6 is placed the main head 17 which has an interior baffle or wall 18 adapted to divide the tubes into two series, one of which is the downflow series and the other of which is the upflow series. The chamber 19 is connected to the water inlet and the chamber 20 to the water outlet, so that, as viewed in Figure 1, the downflow tubes are to the left of the baffle 18 and the upflow tubes to the right. The outer end of the head 17 is closed by a cover 21 between which and the head is another gasket 22, the cover being secured by means of the studs 23 and nuts 24.

Between the main head 17 and a suitable supporting flange 25 on the exterior of the shell 4 I clamp the tube-circulation connecting member 26 which rests on a carefully machined seat 27 on the flange 25. This connecting member is in the form of a ring, as shown to best advantage in Figure 2, and is provided with a water inlet passage 28 and a water outlet passage 29, both of which are suitably flanged as at 30 and 31 for connection to the piping (not shown) through which the cooling fluid is supplied to and withdrawn from the unit. The head, of course, is provided with corresponding inlet and outlet passages 28a and 29a which are adapted to register with the passages 28 and 29, respectively. The passages 28 and 28a and 29 and 29a have their opposing faces carefully machined so as to ensure accurate seating and are made tight by the introduction of gaskets 32, these gaskets lying in a horizontal plane which passes approximately through the mid plane of the tube sheet 6. Between the head 17 and the upper face of the sheet 6 there is another gasket 33 so that all fluid joints are tightly sealed.

In the event of damage to any of the gaskets any leakage of either of the fluids would pass out through the vent 41 between the gasket 16 on the one hand and the gaskets 32 and 33 on the other hand. In other words, fluid from the interior of the shell leaking past the gasket 16 could not reach the fluid which circulates through the tubes and the passages 28-28a and 29-29a should either of the gaskets 32 and 33 be defective because it would enter the vent 41 before it could do so from whence it would be discharged to the exterior of the exchanger. In addition, such discharge would serve as a telltale so that proper repairs to the affected gaskets could be made.

The ring 26 is positioned and held on the flange 25 by means of the studs 34 and the nuts 35, the studs passing through suitable apertures in the flange 25. The parts are clamped in position and all joints made absolutely tight by means of the studs 36 which are secured in threaded openings 37 in the flange 25, the studs extending upwardly through apertures in the flange 38 on the main head 17 and nuts 40 being applied at the upper ends of the studs.

It will now be clear that my invention makes

it possible to construct the exchanger in such a way as to employ whatever type of metal or alloy may be best suited for each of the two fluids involved, to prevent leakage of either fluid into the other, and, at the same time, to provide for the removal of the tube bundle without disturbing any of the piping connections for either fluid. In connection with the latter feature, all that is necessary to do is to remove the upper

10 head and then withdraw the tube bundle with its tube sheets through the top opening, the lower head being left in place on the lower sheet or first removed as desired. It is also possible to substitute in the same shell a tube assembly and 15 tube-circulation connecting member of a different metal or alloy so that the exchanger can be adapted to some other field of service, if desired.

To revert again to the specific use of cooling oil by means of sea water it will be seen that my 20 invention makes it possible to construct the shell 4 entirely of steel and thereby secure the strength and high melting point of that metal in order to provide a flow path for the oil around the exterior of the tubes, which flow path pro-

25 vides a great margin of safety in the handling of this fluid in dangerous installations. The tube sheets, heads and connecting ring may all be made of bronze or other corrosion resistant alloy so that the entire flow path for the cooling medium (salt water in marine installations) is composed of this metal and therefore strongly resists the corrosive action of the water. The various seats are accurately machined and when the gaskets are introduced and the head drawn down 30 against the flange 25 as described, it is obvious that absolutely leak-proof joints are provided and that the structure is exceedingly strong and rigid. The arrangement effects a large saving in the quantity of special alloy needed and at the same 35 time provides the greatest possible measure of strength and resistance to melting for those portions of the structure in which the oil is conveyed and which come into direct contact with the surrounding atmosphere.

I claim:

1. In a tube and shell type heat exchanger, an external flange near an end of the shell, a separable ring-like tube-circulation connection member surrounding the shell and adapted to seat on said flange, said member having an inlet passage and an outlet passage for the fluid which is to be passed through the tubes, a tube sheet having a seat on the end of the shell, tubes connected to said sheet, the outer margin of the tube sheet lying to the inside of said connection member, a head adapted to seat on said tube sheet, said head having corresponding inlet and outlet passages, the passages in said head and those in said connection member meeting in a 55 region which lies beyond the outer margin of the tube sheet, and means for securing the head against the tube sheet with the inlet and the outlet passages in registry, whereby to complete a fluid flow path through the interior of said tubes, the head and the tube sheet with its tubes being removable without removing said connection member, and the head and the connection member being removable without removing the tube sheet with its tubes.

2. The device of claim 1 in which the securing means for the head includes means for clamping the connection member between the head and the shell flange.

DANIEL RAYMOND McNEAL
